CORONA ELIMINATION IN GENERATOR
END WINDINGS

Charles F. Hill, Edgewood, and Leo J. Berberich,
Forest Hills, Pa., assignors to Westinghouse
Electric & Manufacturing Company, East Pitts-
burgh, Pa., a corporation of Pennsylvania

Application August 6, 1941, Serial No. 405,572

15 Claims. (Cl. 171—206)

Our invention relates to methods and means for eliminating corona in the end-windings of high-voltage alternating-current generators or other electrical machines having windings disposed in air or other gaseous medium.

The dangers of corona, in high-voltage machines, are now well known, and there have been proposed many different corona-preventing means, mostly imperfect or of limited application. As explained in a patent of Charles F. Hill, No. 1,784,989, corona is a gaseous-ionization phenomenon which occurs in a gaseous medium when it is subjected to an electrostatic voltage-gradient high enough to accelerate the ionized electrons (which are always present) to a sufficiently high velocity, during the free path of travel of such electrons, so they will have a sufficiently high velocity, by the time when they strike against a neutral molecule of the gas, to ionize that molecule as a result of the force of the collision. In high-voltage machines, corona can be so destructive as to destroy enough of certain organic insulation to start an arc which can cause a short-circuit within a matter of a few months. The corona-hazard has heretofore limited the practical design and use of high-voltage dynamo-electric machines.

As set forth in the Hill patent just mentioned, the elimination of corona in the small gaseous spaces existing within the slots of a dynamo-electric machine has been successfully effected by coating the straight slot-lying-portions or coil-sides of the insulated windings with aquadag, or a point which will be referred to, in our present specification, as a "conducting" paint. This "conducting" paint constitutes an adhering surface or layer, which adheres closely against the surface of the insulation surrounding the conductors of the winding, so that there is no air-gap therebetween, and hence no corona therebetween; and this "conducting" paint has a sufficient amount of electrical conductivity so that all portions of the surface of said aquadag or "conducting" paint are at very nearly the same electrical potential, the resistance-drop within the painted coating, along the length of the insulated conductor, being of a very small order of magnitudes with respect to the voltage-gradient which is necessary to produce corona in air or whatever other gaseous medium is utilized within the machine. This so-called "conducting" coating of aquadag, or the equivalent, necessarily has, however, a certain amount of resistivity, which may be of the order of from 100 to 10,000 ohms surface-resistivity, more or less, which is

needed in order to prevent such coating from short-circuiting the laminations of which the iron core-member of the machine is composed.

The end-windings of high-voltage generators, or the portions of the windings and the winding-terminals which extend out beyond the slotted core-iron, still present difficulties from the standpoint of corona. There are several reasons, which need not be discussed herein, why it is not generally desirable or practical to coat the entire surface of the insulated end-windings with aquadag or other painted coating having as high a conductivity as has been successfully utilized in the slot-enclosed straight-portions or coil-sides of the winding. We utilize a fairly high resistivity, as set forth in this application, in order to prevent corona where the paint ends on the terminal-leads of the winding, and to reduce the voltage-stress on numerous taped joints near the loops of the end-winding portions of the coils.

The problem of the elimination of end-winding corona is aggravated, also, by the limited available space, which results in close spacing between insulated conductors having a relatively high potential-difference therebetween, and by the practical necessity, in any actual machine, for utilizing various spacing-blocks and cross-lashings for holding the various elements of the end-windings in rigid, predetermined spaced relation with respect to each other, and for securing certain portions of the end-windings to some sort of supporting-member which must be secured to the stator-frame or other grounded portion of the machine.

It should be understood that the solid insulation surrounding the end-winding conductors (considered, for a moment, as single conductors in space), operates as a capacitance dielectric which is operated upon, by the alternating voltages of the conductors, to produce capacitance charging-currents which, if not carried away, will produce a surface-voltage, on the surface of the insulation, nearly equal to, but possibly out of phase with, the voltage of the conductor inside of the insulation. It should also be understood that, at all points, wherever the surface of an insulated high-voltage conductor is spaced, in a gaseous medium, from a surface at any other potential (whether the surface of another insulated conductor carrying alternating currents, or a grounded surface), there is danger of corona, and this danger must be carefully eliminated when machines are designed for higher-than-normal alternating-current voltages.

It is an object of our invention to provide a

novel corona-eliminating means in which the entire surface of the end-windings, including their associated spacing-blocks, cross-lashing, supporting-blocks, and supporting-fastenings to ground-ed frame-parts, are all coated with an adherent semi-conducting paint or compound having a preferred range of surface-resistivity (for the thickness of the semi-conducting sheath which we use, ranging probably from 2 mils to 15 mils, more or less), said surface-resistivity ranging from 5 to 20 megohms, or any other high value (perhaps in the range from the order of 1 meg-ohm or less, up to 100 megohms or more), or such other value as is necessitated by the magnitudes of the alternating voltages which are present in the winding-conductors, and by the number and extent of the interconnections between the surfaces of the different insulated end-winding conductors of the same or different phases, and between such insulated-conductor surfaces and adjacent ground-connected conductors. It is necessary that, at no point, shall there be a corona-producing potential-gradient, either in an air-space extending away from a painted surface and between conductors at different potentials, or linearly along any painted surface. At the same time, the resistivity of the semi-conducting coating or painted surface must, at all places, be sufficiently high to prevent the development of any objectionable amount of ohmic heating-losses in the coating, while the coating is carrying the capacity-induced charging-currents which flow therein.

It is a further object of my invention to utilize the same semi-conducting coating to cover all of the surface of the insulated conductors comprising the high-voltage winding of a dynamo-electric machine, including the straight coil-sides which lie within the slots of the core, as well as the entire end-windings, and the spacers, abutments, lashings, and supports thereof—this being done either with, or without, the addition of an extra coating of relatively good-conducting material (such as aquadag) on the straight coil-sides which lie within the slots.

It should be understood that the terms "conducting" and "semi-conducting," as here used, are relative terms, so used because the resistivity of one coating is of the order of 1000 or 100,000 times that of the other. It should be understood, at the same time, that the resistivity of the so-called "conducting" or aquadag coating is many times that of a metal sheath, say copper, of comparable thickness.

A still further object of our invention is to provide a novel means and manner for providing a semi-conducting coating on the insulation of an insulated electrical conductor, comprising the process-steps and the resultant product of applying, first, a painted coat of a semi-conducting paint-compound, and while the painted coat is still wet, wrapping the painted insulated conductor tightly with a porous tape which is preferably of woven glass, but which may be of cotton, asbestos, or other porous materials, applied so tightly that the wet paint penetrates through the pores of the tape, and while the paint is still wet, finally coating the taped surface with a final coat of the same, or a similar paint.

A still further object of our invention is to provide a corona-eliminating means and method for treating the end-winding region of a dynamo-electric machine, in which only one grade or kind or resistivity of semi-conducting paint-compound need be utilized, for all parts and portions of the

treated surfaces, which enormously simplifies the shop-practices necessary in the manufacture of the machine.

With the foregoing and other objects in view, our invention consists of the materials, parts, structures, combinations, and methods herein-after described and claimed, and illustrated in the accompanying drawing, in which:

Figure 1 is a fragmentary longitudinal sectional view of an end-portion of a high-voltage three-phase synchronous generator embodying our invention in a preferred or illustrative form of embodiment.

Fig. 2 is a developed plan-view of a portion of three coils of a high-voltage stator-winding, as viewed from the inside of the stator-bore, on a somewhat larger scale than Fig. 1, with the paint which is applied after the winding is in place shown in section.

Fig. 3 is a longitudinal sectional view, on a still larger scale, of the end-windings, approximately on the plane indicated by the line III—III of Fig. 2, with the paint which is applied after the windings are in place shown in section, and

Fig. 4 is an enlarged transverse sectional view of the conductor, with its various coatings, the coatings being exaggerated considerably in thickness, for clarity of illustration and explanation, the section-plane being indicated, for example, by the line IV—IV in Figs. 1, 2 and 3.

In Fig. 1, we have shown a portion of a three-phase high-voltage generator comprising a stator-member 5 and a rotor-member 6, the latter being mounted upon a shaft 7. The rotor-member 6 is, or may be, the usual rotor-member of a synchronous generator, having the usual direct-current windings and damping windings which need not be described, as they are conventional and constitute no particular part of our invention, except that a synchronous machine is provided. The stator-member 5 is shown as comprising a core-member 8 comprising a plurality of bundles of iron or steel laminations 9 which are centrally bored, as indicated at 11, to provide the air-gap within which the rotor-member rotates. The stator-core 8 is provided with a plurality of slots 14, at its bore 11, for receiving the straight coil-side portions 15 of the insulated high-voltage windings of the machine, said windings being indicated in their entirety by the numeral 16, and comprising the slot-lying, straight coil-sides 15, and the end-windings 17.

It has heretofore been known, to brace and space the various portions of the end-windings by means of suitable bracing, spacing, lashing, and supporting-means which have taken a number of different forms. A representative type of bracing is shown, in Figs. 1, 2, and 3, with certain modifications and improvements in accordance with my invention, as will subsequently be described. Thus, the straight coil-sides 15 extend a certain distance out beyond the end of the iron core 8, before the conductors are bent, as indicated at 20 (Fig. 2), and these straight-side extensions 15, at points close to the end of the core 8, are braced by means of split, channel-shaped, insulating blocks or wedges 21, which are driven into place and are lashed to the respective coil-sides by lashings 22. These lashings may be glass-rope or cord, or any suitable porous insulating cordage or taping, which may be utilized for all of the lashings which will be referred to in the subsequent description. The straight-portion extensions 15 of the coil-sides may also be cross-lashed, as indicated at 23, at

a point between the blocks 21 and the first end-turn bend 20, as shown more clearly in Fig. 3, which shows the cross-lashing 23 between the top and bottom conductors lying in any slot.

At various points along the end-windings 17, a plurality of laterally disposed spacing-blocks 25 are disposed between the insulated conductors coming from adjacent slots, said conductors being lashed together, with said blocks 25 in between, by means of a suitable lashing 26, as shown in Fig. 2. In some instances, also, as shown in Fig. 1, additional insulating spacing-blocks are interposed between the conductors coming from the top and bottom layers of the windings lying in the various slots 14 of the stator-core 8, these last-mentioned spacing-blocks being indicated at 27, and being suitably lashed to the respective end-winding conductors, as indicated at 28.

The stator end-turns 17 are usually provided with cross-connections 29 for the coils.

It is universally customary, also, to support the end-windings 17 in some fashion, various means being utilized for this purpose, the particular supporting-means illustrated in Figs. 1 and 3 comprising a plurality of insulating pieces or brackets 30 which extend out from, and are supported by, the end-portions 31 of the stator-core 8, or the end-plates which clamp the core in place. In some instances, the end-winding supports, corresponding to the brackets 30, are made of conducting material suitably insulated from the end-windings 17. In any case, there must be a supporting connection from the end-windings 17 to some grounded conducting portion (such as 31) of the stator-frame 5. In the illustrated form of embodiment, various portions of the outer layer of the end-windings 17 are lashed to the insulating supporting-brackets 30, by suitable lashings 32.

Some, or all, of the bracing, lashing, and supporting-means, 21 to 32, which have just been described, or their equivalents, are commonly utilized in large generators of the type to which our invention applies; and we do not mean to imply that these features are broadly new. In accordance with our present invention, however, we have introduced modifications in these features, and in the high-voltage winding-conductors 16 themselves, and these modifications will now be described.

As shown in Fig. 4, the high-voltage winding 16 is made up of insulated conductors 34 comprising an inner copper conductor 35 which is surrounded by a compactly applied, usually impregnated, insulation 36 of suitable thickness for withstanding the voltage of the conductor 35, with a suitable factor of safety. The conductor 35, with its insulating cover 36, together constitute what we refer to as the insulated conductor. In accordance with our present invention, the surface of this insulated conductor 35-36 is specially treated, preferably along the entire length of the conductor, including the straight, slot-lying coil-side portions 15, the end-winding portions 17, the cross-connections for the coils, and the terminal-leads of the machine. Our method of treatment of the surface of these insulated conductors 35-36 is to apply a semi-conducting, adherent, painted-on layer or coating, which may be applied in many different ways, and which may be a single coating or a plurality of coatings of any desired thickness.

We prefer, however, to apply the semi-conducting coating in a manner which is illustrated, in an exaggerated manner, in Fig. 4, wherein the 75

thicknesses of the semi-conducting coating-portions are considerably exaggerated, (out of proportion to the size of the conductor 35 and the thickness of the conductor-insulation 36), in order to facilitate the showing, without making the figure too large. In our preferred method of fabrication for the semi-conducting coating, we first coat the surface of the conductor-insulation with a semi-conducting paint-compound 40, and then, 10 while the painted layer 40 is still wet, we preferably tightly apply a layer of porous tape 41, which is preferably a braided glass tape, or perhaps 10 mils thickness, but which may be made of other porous insulating materials, said tape 41 being applied so tightly that the fibers or threads of the tape are pressed into the wet paint-layer 40 so that the semi-conducting paint 40 oozes through the pores or interstices of the tape, and then, while the paint is still wet, we preferably 20 apply a final layer 42 of this same semi-conducting paint-compound. In this manner, the porous tape serves to fix or hold the semi-conducting paint, so as to reinforce the same against any possible tendency to split or crack away from the surface to which it is applied.

The semi-conducting paint-compound which we utilize for our painted layers 40 and 42, and for other painted semi-conducting layers to be subsequently described, is a compound which is 30 made up of a large proportion, by volume, of a finely powdered semi-conducting substance, and a relatively small proportion, by volume, of a suitable paint-medium or varnish which serves as a binder which is capable of drying out after the paint-compound has been applied. We need to 35 utilize a large proportion of the powdered semi-conducting material, so that we will have approximately particle-to-particle contact of the grains of the powder, in the finished painted 40 semi-conducting surface, as distinguished from a construction in which the conducting or semi-conducting particles are so few in number that they will be separated and insulated from each other by relatively thick layers of the paint or varnish-material in the finished coating. The 45 disadvantage of a semi-conducting paint-compound, which has only a relatively small proportion of powdered conducting or semi-conducting material in it, is that, when high voltages are applied to the finished semi-conducting surfaces, after the paint has dried, the insulating layers of paint or varnish, which separate the conducting or semi-conducting grains, will become punctured by electrical stress or flashovers, so as to cause the conductivity of the coating as a whole to increase or vary in an erratic and undesirable fashion. We believe it is to be necessary, therefore in fabricating our semi-conducting paint-compound, to utilize a relatively large amount of semi-conducting powdered material, which is held together with not too large an amount of paint-binder or varnish, and to control the conductivity of the resulting paint-compound by controlling, or properly choosing, the conductivity of the powdered material, rather than by varying the amount of the powdered material.

For the powdered material which we utilize in our paint-compound as just described, we may utilize a suitably controlled wood-char, similar to that which is described in a patent to Leon McCulloch, No. 2,050,357, patented August 11, 1936, and assigned to the Westinghouse Electric & Manufacturing Company. Such wood-chars are very imperfectly carbonized cellulose-materials, the degree of carbonization of which, and

hence the amount of conductivity, is determined by a proper choice of the firing-temperature, as described in the McCulloch patent.

It is highly desirable, however, to utilize a semi-conducting paint-compound which will be highly stable, during a life-time of use, without gradually increasing in resistivity, or otherwise changing its resistivity, during the life of the machine to which the compound is applied. While we lack conclusive life-tests on various semi-conducting paint-materials which could be utilized for our purpose, there is room for the belief that more stable results could probably be obtained by the use of some inorganic semi-conducting powdered material, of the proper conductivity or semi-conductivity, in place of the wood-char just mentioned.

One such semi-conducting powdered material which we are considering, as the semi-conducting part of our paint-compound, is a specially treated, powdered titanium dioxide, which has been partially reduced in a hydrogen furnace, the amount of reduction being controlled by the temperature of the furnace and the time in the furnace, so as to produce a partially reduced titanium-dioxide powder having the desired degree of conductivity or semi-conductivity. This powder would then be mixed with a suitable quantity of paint-binder or varnish, usually requiring a paint-volume at least equal to the powder-volume. A suitable ratio of powder to varnish, in mixing the semi-conducting paint-compound which we utilize in the manner described herein (whatever the nature of the semi-conducting powder), can be determined by adding sufficient powder, to the varnish, to produce a dull matt surface after the varnish has dried or the solvent has been removed. A shiny surface indicates that too much varnish has been added. The particular paint-compound, utilizing partially reduced titanium-dioxide powder, which has just been referred to, will be made the subject of another application, assigned to the Westinghouse Electric & Manufacturing Company.

In accordance with our invention, the entire assembly of spacing-blocks, lashings, coil cross-connections, and supports, 21 to 32, which are applied after the high-voltage winding 16 has been inserted in place on or in the dynamo-electric machine, are all painted over, with one or more coatings 43 of a semi-conducting paint-compound such as has just been described, so as to make, in effect, a plurality of semi-conducting charging-current-carrying paths, between a plurality of different portions of the conductor-coating 42 of the end-windings, and other adjacent surfaces, whether surfaces of different painted insulated conductors, or surfaces of grounded metal members. Preferably, the various lashings 22, 23, 26, and 32 are applied in the manner already described for the tape 41; namely, by first painting the surface to be lashed, with our semi-conducting paint-compound, then applying the lashing, and then repainting while the first paint-coat is still wet. Preferably, also, the insulating spacing-blocks, such as 21, 25, and 27, are painted before being applied, and again afterwards; although, at least in the case of the split wedge-blocks 21, it has been found undesirable to paint the wedge-surfaces which have to slide against one another, while the blocks are being pounded into place, this being merely a matter of avoiding excessive friction which would hamper the application of the blocks.

Regardless of the specific preferred details of

application, the essential feature, however, is that the semi-conducting paint shall make a semi-conducting electrical connection between the various surfaces which are to be joined, as previously described, so that the various capacitor charging-currents are conducted away from the several surfaces in such manner as to avoid the possibility of obtaining a corona-inducting potential-gradient at any point.

10 A very considerable variation is tolerable, in the permissible or desirable resistivity or resistivities of the semi-conducting coatings. One rule which we have found helpful from the designer's standpoint, as guiding us toward the correct order of magnitude of conductivity to choose, or a desirable order of conductivity, is to choose a semi-conducting coating having a surface-resistivity such that, before any spacing or supporting blocks are applied, and before any lashing or cross-lashing is applied, the resistivity of the semi-conducting coating on the end-windings 17 is such that there will be a relatively small difference in voltage between the internal conductor-proper 35 and the semi-conducting coating 40-42, at the central loops 44 (Fig. 2) at the ends of the end-windings. This relationship is subsequently altered, of course, when the cross-connections are applied, but the rule just indicated affords a basis for a very approximate rule-of-thumb method for determining one suitable value for the surface-resistivity of the semi-conducting coating. The general range of values of the surface-conductivities has already been indicated, in the preliminary portions of this specification.

35 The semi-conducting layer 40-42, as above described, may be applied only to the end-windings 17, and to the various blocks, lashings, and supporting-means or adjacent grounded surfaces in the vicinity thereof, but we prefer, as previously indicated, to extend this semi-conducting coating over the entire insulated winding 16, including the straight coil-sides 15 which will be thus coated before the coil is inserted in place in the stator-slots 14. We believe that the semi-conducting coating 40-42, as described, is of sufficient conductivity, and is satisfactory in every way, for preventing corona in the stator-slots 14. If desired, however, and as an extra precaution, a relatively "conducting" coating, of aquadag, or 40 equivalent coating as previously discussed, may be applied to the straight side-portions which are to lie in the stator-slots 14, as indicated at 45, in Figs. 2 and 4. In inserting the coil-sides in the slots 14, it is necessary to make sure that there is an electrical contact between the coated layer of each coil-side and the iron of the slot, as pointed out in the previously mentioned Hill patent.

50 While we have described our invention in a form of embodiment which we now prefer, and while we have explained the invention in accordance with our present understanding of the same, we desire it to be understood that such illustration and explanation are intended only by way of suggestion, and not altogether by way of limitation; and we desire it to be understood that many changes may be made, by way of additions, alterations and omissions, without departing from the essential spirit and objects of our invention.

55 We desire, therefore, that the appended claims shall be accorded the broadest construction consistent with their language.

We claim as our invention:

60 1. A high-voltage alternating-current dynamo-
65 electric machine comprising a stator-member and

a rotor-member operating in a gaseous medium, one of said members having a slotted core-member, and an insulated high-voltage winding comprising slot-lying coil-side portions and end-winding portions, a plurality of different insulating blocking-means and insulated lashings between different insulated conductors of said end-windings, a plurality of grounded insulating supporting-means connected to a plurality of portions of the end-windings, and a semi-conducting adherent coating covering the surfaces of said end-windings and the surfaces of all of said blocking-means, lashings and insulated supporting-means.

2. A high-voltage alternating-current dynamo-electric machine comprising a stator-member and a rotor-member operating in a gaseous medium, one of said members having a slotted core-member, and an insulated high-voltage winding comprising slot-lying coil-side portions and end-winding portions, a plurality of different insulating blocking-means and insulated lashings between different insulated conductors of said end-windings, a plurality of grounded insulating supporting-means connected to a plurality of portions of the end-windings, a semi-conducting adherent coating covering the surfaces of said end-windings and the surfaces of all of said blocking-means, lashings and insulated supporting-means, and a more-conducting adherent coating covering the surfaces of the slot-lying coil-side portions.

3. A high-voltage alternating-current dynamo-electric machine comprising a stator-member and a rotor-member operating in a gaseous medium, one of said members having a slotted core-member, and an insulated high-voltage winding comprising slot-lying coil-side portions and end-winding portions, a plurality of different insulating blocking-means and insulated lashings between different insulated conductors of said end-windings, a plurality of grounded insulated supporting-means connected to a plurality of portions of the end-windings, and a semi-conducting adherent coating covering the entire surface of all of the insulated conductors of both the slot-lying coil-side portions and the end-winding portions of the insulated high-voltage winding, and also covering the surfaces of all of said blocking-means, lashings and insulated supporting-means.

4. The invention as defined in claim 1, characterized by said semi-conducting adherent coating comprising a single grade or resistivity of semi-conducting paint-compound for the entire coating aforesaid.

5. The invention as defined in claim 1, characterized by said semi-conducting adherent coating having a surface-resistivity of the order of a megohm or more.

6. The invention as defined in claim 3, characterized by the portion of the semi-conducting adherent coating, which covers the surfaces of the insulated conductors of the high-voltage winding, comprising a first coat of a semi-conducting paint, a taped layer of porous tape sinking down into said first coat, and a second coat of semi-conducting paint over said taped layer.

7. A high-voltage alternating-current dynamo-electric machine comprising a stator-member and a rotor-member operating in a gaseous medium, one of said members having a slotted core-member, and an insulated high-voltage winding comprising slot-lying coil-side portions and end-winding portions, a semi-conducting adherent

coating substantially covering the surfaces of at least said end-winding portions, a plurality of means, at a plurality of different points, for semi-conductingly blocking apart, and semi-conductingly lashing together, different coated conductors of said end-windings, and a plurality of grounded means for semi-conductingly supporting a plurality of portions of the end-windings.

10 8. The invention as defined in claim 7, characterized by the coating on said end-winding portions comprising a first coat of a semi-conducting paint, a taped layer of porous tape sinking down into said first coat, and a second coat of semi-conducting paint over said taped layer.

15 9. The invention as defined in claim 7, characterized by said semi-conducting adherent coating having a surface-resistivity of the order of a megohm or more.

20 10. A high-voltage alternating-current dynamo-electric machine comprising a stator-member and a rotor-member operating in a gaseous medium, one of said members having a slotted core-member, and an insulated high-voltage winding comprising slot-lying coil-side portions and end-winding portions, a semi-conducting adherent

25 coating substantially covering the surfaces of the insulated conductors of said winding, a plurality of means, at a plurality of different points, for semi-conductingly blocking apart, and semi-conductingly lashing together, different coated conductors of said end-windings, and a plurality of grounded means for semi-conductingly supporting a plurality of portions of the end-windings.

30 35 11. The invention as defined in claim 10, characterized by the coating on the slot-lying coil-side portions being more conducting than that on the end-winding portions.

40 12. The invention as defined in claim 10, characterized by the coating on said end-winding portions comprising a first coat of a semi-conducting paint, a taped layer of porous tape sinking down into said first coat, and a second coat of semi-conducting paint over said taped layer.

45 13. A high-voltage alternating-current dynamo-electric machine comprising a stator-member and a rotor-member operating in a gaseous medium, one of said members having a slotted core-member, and an insulated high-voltage winding comprising slot-lying coil-side portions and end-winding portions, a semi-conducting adherent

50 coating covering the entire surface of all of the insulated conductors of both the slot-lying coil-side portions and the end-winding portions of the insulated high-voltage winding, a plurality of means, at a plurality of different points, for semi-conductingly blocking apart, and semi-conductingly lashing together, different coated conductors of said end-windings, and a plurality of grounded means for semi-conductingly supporting a plurality of portions of the end-windings.

55 60 14. The invention as defined in claim 13, characterized by the coating on the slot-lying coil-side portions being more conducting than that on the end-winding portions.

65 15. The invention as defined in claim 13, characterized by the coating on said end-winding portions comprising a first coat of a semi-conducting paint, a taped layer of porous tape sinking down into said first coat, and a second coat of semi-conducting paint over said taped layer.

CHARLES F. HILL,
LEO J. BERBERICH
